C. Brown & Co.

UNITED STATES PATENT OFFICE.

LEWIS A. SHORT, OF SWARTZ CREEK, MICHIGAN.

FENCE.

SPECIFICATION forming part of Letters Patent No. 628,167, dated July 4, 1899.

Application filed September 21, 1898. Serial No. 691,521. (No model.)

To all whom it may concern:

Be it known that I, LEWIS A. SHORT, a citizen of the United States, residing at Swartz Creek, in the county of Genesee and State of Michigan, have invented a new and useful Fence, of which the following is a specification.

My invention relates to wire fences, and has for its object to provide a fence of this class wherein the vertical strength of the panels is increased by trussing and wherein the longitudinal members of the fence are so connected and arranged with relation to each other that the severing of a member in one panel does not affect the next panel on either side, each longitudinal member of the fence forming, respectively, a runner and a truss member in adjoining panels.

Further objects and advantages of this invention will appear in the following description, and the novel features thereof will be particularly pointed out in the appended claims.

In the drawings, Figure 1 is a view of a fence constructed in accordance with my invention. Fig. 2 is a view of the same in the course of construction and before the longitudinal members have been connected and twisted to form vertically-bracing trusses. Fig. 3 is a diagrammatic view showing the runs of two strands, of which the portions located in alternate panels are intertwined to form the truss-braces.

Similar numerals and letters of reference indicate corresponding parts in all the figures of the drawings.

In the construction of fence which I prefer each span, as between spaced posts 1 and 2, may be divided by one or more pickets 3 to 40 form a plurality of panels, said pickets being supported by the wire members of the fence. In the construction illustrated the span between the posts 1 and 2 is divided by two pickets to form panels A, B, and C, and also 45 in the construction illustrated there are upper and lower plural-strand marginal runners, between which are arranged a number of intermediate runners, as four. Each runner of one panel, however, is not a continuation of the corresponding runner of the adjoining panel, but, on the other hand, is a continuation of a truss member of such adjoin-

ing panel, these truss members being arranged in pairs and being intertwined at points approximately at the centers of the panels to 55 stiffen the structure vertically.

In constructing a fence embodying my invention I employ on the posts and pickets a number of keepers or equivalent fastening devices 4, which is equal to the number of 60 marginal and intermediate runners which are to be formed. Through each of the terminal or marginal keepers I extend three strands of wire or like material, and through each of the intermediate keepers I extend two 65 strands, whereby each keeper secures a plurality of strands to the uprights of the fence. As above indicated, each marginal runner is of plural-strand construction, and in practice I prefer to form said marginal runners 70 by the intertwisting of two of the strands extending through each marginal keeper, different pairs of such strands, however, being used in adjoining panels. Thus the strands *a* and *b* are intertwined in panel A to form 75 the upper marginal runner, while the third marginal strand *c*, which extends through the same keepers as the strands *a* and *b*, is deflected from the line of the marginal runner to form the upper member of a truss-brace, 80 while in panel B the strands *b* and *c* are intertwined to form the upper marginal runner, and the strand *a* is deflected to form the upper member of a truss-brace, and in panel C the strands *a* and *b* are again intertwined 85 to form the upper marginal runner, while the strand *c* is deflected for a purpose similar to that above indicated.

The strands *d* and *e*, which pass through the uppermost intermediate keepers in the panel 90 A, form, respectively, the uppermost intermediate runner and the upper member of a truss-brace, which is below that of which the strand *c* forms a member, while in panel B the relative positions of the strands *d* and *e* are reversed, the strand *e* forming the uppermost intermediate runner, while the strand *d* is deflected to form the upper member of a truss-brace, which is below that of which the strand *a* forms a member. In panel C the positions 95 of the strands *d* and *e* are again reversed to arrange them as in panel A. In the same way throughout the structure the strands *f*, *g*, *h*, *i*, and *k*, *l*, which pass, respectively, through the

intermediate keepers below that engaged by the strands *d e*, are disposed alternately in adjoining panels, that strand which forms the runner in one panel being deflected from the line of the runner in the next panel to form a member of a truss-brace, and also the strands *m n o*, which pass through the lowermost keeper, are disposed as described in connection with the strands *a b c*. Thus in panel A the strands *a b* and *m n* form the upper and lower marginal runners and the strands *d f*, *h*, and *k* form the intermediate runners, while the strands *c* and *i* are drawn together and intertwined at the center of said panel A, the strands *e* and *l* are correspondingly drawn together and intertwined to form a lower brace, and the strands *g* and *o* are correspondingly connected at a still lower point. These intertwined truss members may be effectually connected by inserting a pin or bar between them and turning it to twist said members in the opposite direction from a central point, as shown clearly in Fig. 1. It will be seen that each arm of a truss-brace intersects one or more arms of other braces and also one of the strands forming a runner, and in the vertical planes of these intersections I arrange stays 5, terminally attached to the marginal runners and looped, respectively, in the planes of the intermediate runners, as shown at 6, and engaged with the intersecting members of the fence. This locking of the members at their points of intersection prevents relative displacement, and the stays are arranged to intersect those diamonds formed between the arms of the braces, while the remaining intervals between the runners are divided, respectively, by the intertwined central portions of the braces and by the diagonally-disposed portions of the brace-arms located outside of or beyond said stays, thereby forming a fence of which the intervals between the members are small and are incapable of allowing the passage of small stock.

In panel B the marginal runners are formed by the strands *b c* and *n o*, the intermediate runners by the strands *e g i*, and *l*, while the strands *a d f h k*, and *m* are intertwined to form the truss-braces, substantially as described in connection with panel A.

From the above description it will be seen that I have constructed a fence whereby if a strand is broken in one panel the positions of the parts in the adjoining panel will not be affected. For instance, should the strand *l* of panel B and forming the lowermost intermediate runner be broken it will not affect either of the runners of the adjoining panels A and C. The continuations of the runner strand *l* form the lower members of the central or intermediate truss-braces of the panels A and C, and even should the tension exerted by these truss-braces be sufficient to cause them to yield slightly by reason of a break the remaining members of the panels A and C will retain their normal positions. Furthermore, the specific arrangement of the

stays which engage the strands at their points of intersection serves to prevent relative displacement in case of the breakage of a strand in one of the panels; also, should one of the strands of the marginal runner be broken in panel B it will not affect the marginal runners of either of the panels A and C, for the reason that only one strand of the marginal runner in one panel is a continuation of a strand in the marginal runner of the adjoining panel. Hence should the strand *o* of panel B be broken it can affect only the lowermost truss-brace of the panel A and not the lower marginal runner of the panel A.

A further advantage of the construction resides in the fact that the tension of the various members may be taken up at the points of looseness. For instance, looseness of the runner members in panel A may be taken up by tightening the brace of panel B, and vice versa.

Various changes in the form, proportion, and the minor details of construction may be resorted to without departing from the spirit or sacrificing any of the advantages of this invention.

Having described my invention, what I claim is—

1. A fence having marginal and intermediate runners, and truss-braces of which the members equal in number with the runners intersect the intermediate runners and are intertwined at their intermediate points, and staysterninally attached to the marginal runners and provided respectively in the planes of the intermediate runners with loops each of which engages an intermediate runner and a brace member at their point of intersection; substantially as specified.

2. A fence having marginal and intermediate runners, and truss-braces having centrally-intertwisted members of which the terminal arms are divergently disposed to intersect the intermediate runners, each intermediate runner of one panel forming one member of a truss-brace of the adjoining panel, substantially as specified.

3. A fence having marginal and intermediate runners, of which the former are of plural-strand construction, and truss-braces consisting of centrally-intertwisted members of which the terminal arms are divergently disposed to intersect the intermediate runners, each intermediate runner of one panel being extended to form a member of a truss-brace in the adjoining panel, and one strand of each marginal runner of one panel being correspondingly extended to form one member of a truss-brace in said adjoining panel, substantially as specified.

4. A fence having uprights provided with keepers corresponding in number with the runners, and a plurality of strands extending through each keeper, one strand in each keeper being stretched between the uprights in one panel to form a runner, and being deflected in the adjoining panel to form a mem-

ber of a truss-brace, and terminally remote truss-brace members being centrally inter-twisted, substantially as specified.

5. A fence having uprights provided with a plurality of keepers corresponding in number with the runners, and a plurality of strands extending through each keeper, each strand in adjoining panels respectively forming a runner and a member of a truss-brace, and

the truss-brace members being centrally inter-twisted in pairs, substantially as specified.

In testimony that I claim the foregoing as my own I have hereto affixed my signature in the presence of two witnesses.
